UNITED STATES PATENT OFFICE.

WALTER E. BROWN, OF NEW YORK, N. Y., ASSIGNOR TO THE PEELLE COMPANY, OF NEW YORK, N. Y., A CORPORATION OF NEW YORK.

AUTOMATIC DOOR-CLOSING DEVICE.

1,114,854.

Specification of Letters Patent.

Patented Oct. 27, 1914.

Application filed May 21, 1913. Serial No. 768,948.

To all whom it may concern:

Be it known that I, WALTER E. BROWN, a citizen of the United States, and a resident of New York city, borough of Manhattan, in the county of New York and State of New York, have invented certain new and useful Automatic Door-Closing Devices, of which the following is a specification.

This invention relates to automatic door closing devices, and the object of my invention is to provide a new and improved automatic door closing device, which is especially adapted and designed for automatically closing vertically movable doors for elevator shafts and the like, in case of fire, which device is simple in construction, durable and reliable and effective in action.

In the accompanying drawings in which like letters of reference indicate like parts in all the figures: Figure 1 is an elevation of a pair of elevator doors provided with one embodiment of my improvement. Fig. 2 is a horizontal sectional view on the line *a—a* of Fig. 1. Fig. 3 is an enlarged detail elevation of the weight, latch and guide rod. Fig. 4 is a horizontal view on the line *b—b* of Fig. 3.

The doors 1 and 2 are mounted to slide vertically on guides 3, and are connected by chains and rods 4 and 5 attached to the doors and passing over pulleys 6 so that the two door sections move toward each other in closing and from each other in opening. The doors are so weighted and balanced that when opened to any desired degree they remain in position, and so that when opened a comparatively small additional load acting on the upper door causes it to descend and the lower door to rise until their adjacent edges contact and the door opening is completely closed. The matter so far described is old and well known and forms no part of my present invention.

The upper door 1 is provided at each lower corner with an arm 7 which extends beyond the side of the door and beyond the inner edge of a vertical rail 8 which is at right angles to said arm. Adjacent to and outside of said rail a vertical guide rod 9 extends from a bracket 10 directly beneath the pulley 6 to a bracket 11 projecting from the outer side of the rail 8 and on said rod a weight 12 is mounted to slide freely, said weight being equal to a trifle more than one half of the weight required to move the up-

per door section 1 downward and the lower door section 2 upward. If the weight required to so move the door is fifty lbs. then each weight 12 would be about twenty-five lbs. more or less. The weight 12 is provided at its upper end with an arm 13 projecting beyond the edge of the rail 8 to such a distance that it is in the path of the arm 7 projecting laterally from the corresponding lower corner of the door; this arm 13 on the weight being above the arm 7, on the corresponding lower corner of the door. A vertical guide plate 14 is provided at right angles to the rail 8. At the upper end of the rod 9 a latch lever 15 is pivoted to the plate 14 at 16.

The sliding weight 12 is provided with a hooked arm 17 the upper end of which can engage the latch lever 15 so that this latch can hold the weight in raised position. The hooked arm slides on the plate 14 which thus serves as a guide to prevent the weight from turning on the rod 9. The ends of the two latch levers 15 opposite the ones on which the hooked arms 17 of the weights are suspended are connected by a wire 18 passed over suitable pulleys 19 and provided with a fusible piece 20. This wire is drawn so taut as to hold both latch levers in horizontal position, thus keeping both weights 12 raised so that they will be directly beneath the pulleys. The doors can be opened and closed manually as usual and will not be interfered with by the weight as this is held higher than the arms 7 on the lower corners of the upper doors and always locked in place. The wire is preferably carried up to and below the lintel of the door opening on the loft room side but may be arranged in any other suitable manner. In case of fire the fusible part 20 in the wire 18 melts thus releasing the latches 15 and permitting the weights 12 to drop downward on the rods 9 until the arms 13 on said weights strike against the upper edges of the arms 7 on the lower corners of the upper door, thereby moving said upper door downward and the lower door correspondingly upward so as to close the door opening completely. Of course if the doors are closed when the fusible part of the wire melts the weights drop without any additional effect but if the doors are partly open or entirely open the released weights, by acting on the arm 7 on the upper doors move

the same downward thereby closing both doors.

Having described my invention what I claim as new and desire to secure by Letters

5 Patent is:—

1. The combination with vertical guide rails for an elevator shaft door, of brackets secured to one of said guide rails, a vertical guide rod secured on said brackets parallel with and adjacent to the guide rail, a sliding weight on said guide rod, a latch for holding said weight raised, a fusible plug controlling said latch and a projection on the door extending laterally beyond the door 15 to be in the path of said weight, substantially as set forth.
2. The combination with an elevator shaft door and vertical guide rails for the same, of brackets secured on one of said 20 guide rails, a guide rod attached to said brackets, a weight mounted to slide vertically on said guide rod, a hook projecting upward from said weight, a latch for engagement with said hook, a fusible means 25 for holding said latch in position and a laterally projecting part on the door extending into the path of said weight, substantially as set forth.
3. The combination with a vertically 30 movable elevator shaft door, of vertical guide rails for the same, a vertically sliding weight adjacent one of said guide rails,

means for guiding said weight in its vertical movement, a projecting plate on said weight, a projecting part extending from 35 the door laterally into the path of said projecting plate on the weight and beneath said plate and means for holding said weight in raised position and a fusible means for releasing said weight, substantially as set forth.

4. The combination with a vertically movable elevator shaft door, of vertical guide rails for the same, brackets secured to one of said guide rails on its face farthest from 45 the side edge of the door, a vertical guide rod secured to said brackets, a weight mounted to slide vertically on said guide rod, a plate projecting from the top of said weight and projecting beyond the edge of the guide rail 50 and an arm on the door extending beyond the edge of the guide rail and into the path of said plate on the weight, a latch for holding the weight in raised position and a fusible device for holding the latch in place, 55 substantially as set forth.

Signed at New York city in the county of New York and State of New York this 19th day of February, A. D. 1913.
